CONTROL PANEL FOR A COMPUTER PLUG BOARD

Paul F. French, St. Louis, Mo., assignor to Sperry Rand Corporation, New York, N.Y., a corporation of Delaware

Filed Sept. 23, 1964, Ser. No. 81,843

Term of patent 3½ years

(Cl. D26—5)

FIGURE 1 is a top plan view of a control panel for a computer plug board showing my new design.

FIGURE 2 is a rear elevational view.

FIGURE 3 is a front elevational view.

FIGURE 4 is a side elevational view thereof as seen from the left of FIGURE 1.

FIGURE 5 is a side elevational view thereof as seen from the right of FIGURE 1.

I claim:

The ornamental design for a control panel for a computer plug board substantially as shown.
